UNITED STATES PATENT OFFICE.

ADOLPH S. ELLISON, OF NEW YORK, N. Y.

BRAID-TRIMMING.

SPECIFICATION forming part of Letters Patent No. 367,339, dated July 26, 1887.

Application filed February 25, 1887. Serial No. 228,872. (No specimens.)

To all whom it may concern.

Be it known that I, ADOLPH S. ELLISON, of the city, county, and State of New York, have invented a new and useful Improvement in 5 Braid-Trimming, of which the following is a full, clear, and exact description.

My invention relates to an improvement in braid-trimmings, and has for its object to provide an article strong and durable, yet having 10 a delicate light appearance.

The invention consists in the construction and combination of the several parts, as will be hereinafter fully set forth, and pointed out in the claim.

15 Reference is to be had to the accompanying drawing, forming a part of this specification, in which the figure of the drawing is a front elevation of a piece of my braid-trimming.

In carrying the invention into effect a strip 20 of braid of any desired width is crinkled and carried at an angle downward, as at A, then bent upon itself twice to form the opposite loops, $a' a'$, which loops are secured in position by warp-threads b . The braid is again crinkled and carried down at an angle, as at A, 25 above mentioned, and two opposing loops, $a' a'$, are again made and secured in position, which process is continued until four or more crinkled zigzag inclined lengths of braid, A, 30 are produced, according to the desired width of the trimming. The last length of braid A is bent upon itself five times, forming thereby as many opposing loops, $b' b'$, which loops are in the same horizontal plane, and are secured 35 in position in similar manner to the aforesaid loops $a' a'$, and form the lower selvage edge of the trimming. The braid is now crinkled and carried upward in a length, B, at an inclination toward the top of the opposing length A 40 and secured to said top, producing the more or less V-shaped opening D. From this point the braid is bent upon itself to form two loops, $a^2 a^3$, in horizontal alignment with the loops $a' a'$, formed in the downward zigzag course 45 of the braid. Another length of crinkled braid, B, is then carried at an inclination upward and united to the top of the opposite crinkled length A, forming thereby a second V-shaped opening, D, immediately over the 50 lower similar opening, and so on until the top opening, D, is formed. At this point the braid is bent upon itself five times and five horizontally-arranged loops, $b' b'$, are pro-

duced, forming the top selvage in corresponding manner to the lower selvage edge. The 55 braid is now carried downward again, as in the first instance, and the exact operation duplicated throughout the length of the piece, producing series of aligning V-shaped openings, D, and a series of horizontal rows of 60 opposing loops, $a' a^2 a^3$, as shown in Fig. 1, the top and bottom selvage being formed by the loops $b' b'$.

The number of loops may be varied, if found desirable, without departing from the spirit 65 of my invention.

In defining my invention with greater clearness I would state that I am aware that it is not new to form a trimming of cord or chenile disposed in loops, after the manner shown in 70 my drawing, and connected by longitudinal threads extending through the folded loops; and I make no broad claim to this general form of trimming. My invention is distinctive, first, in the use of braid for this purpose, 75 which, being a flat elastic fabric, (in contradistinction to a hard twisted cord,) makes an entirely different article, in which the braid assumes a flat wide full side view between the points of connection, and is narrowed or 80 crinkled at the folded and connected points, making a full body and a somewhat irregular mesh with graceful folds. This trimming is capable of being washed and ironed without being impaired in beauty or structure, is perfectly flexible in all directions, which adapts 85 it to be placed over irregular curves, can be fastened to a garment by a sewing-machine, and is much cheaper and more durable than silk-covered cord. 90

Having thus described my invention, what I claim as new, and desire to secure by Letters Patent, is—

As an improved article of manufacture, a trimming consisting of a continuous braid arranged in substantially parallel transverse lines, said lines consisting of crinkled inclined portions intervened by double loops, and said lines connected at each edge of the trimming by a selvage of loops, the said lines of 95 braid being united at the loops by lines of thread, substantially as set forth. 100

ADOLPH S. ELLISON.
